United States Patent Office

Des. 184,207
Patented Jan. 6, 1959

184,207

BOTTLE

William H. Baird, Wheeling, W. Va., assignor to Continental Can Company, Inc., New York, N. Y., a corporation of New York

Application December 12, 1956, Serial No. 44,167

Term of patent 14 years

(Cl. D58—8)

The figure is a perspective view of a bottle, showing my new design.

The bottle is circular in cross-section throughout. The side not shown is the same as the side shown.

I claim:

The ornamental design for a bottle, as shown and described.
